Primary Examiner — Darcey E Gottschalk*Assistant Examiner* — Isabelle S Farineau(74) *Attorney, Agent, or Firm* — Workman Nydegger(57) **CLAIM**

The ornamental design for a hexagonal-shaped light fixture, as shown and described.

DESCRIPTION

FIG. 1 is top, right facing perspective view of our new design for a hexagonal-shaped light fixture;

FIG. 2 is a bottom, right facing perspective view thereof;

FIG. 3 is an elevated facing view thereof;

FIG. 4 is an elevated rear view thereof;

FIG. 5 is a top, plan view thereof;

FIG. 6 is a bottom, plan view thereof;

FIG. 7 is an elevated right side view thereof; and,

FIG. 8 is an elevated left side view thereof.

Dotted lines represent portions of the hexagonal-shaped light fixture that form no part of the claimed design.

The hexagonal-shaped light fixture is shown with a symbolic break in its height. The appearance of any portion of the article between the break lines forms no part of the claimed design.
